H. F. CRAWFORD,
DIEING-OUT ATTACHMENT FOR PRESSES,
APPLICATION FILED OCT. 28, 1918.

1,307,041.

Patented June 17, 1919.

UNITED STATES PATENT OFFICE.

HARVEY F. CRAWFORD, OF BROCKTON, MASSACHUSETTS.

DIEING-OUT ATTACHMENT FOR PRESSES.

1,307,041.

Specification of Letters Patent. Patented June 17, 1919.

Application filed October 28, 1918. Serial No. 259,972.

To all whom it may concern:

Be it known that I, HARVEY F. CRAWFORD, a citizen of the United States, residing at Brockton, in the county of Plymouth and State of Massachusetts, have invented new and useful Improvements in Dieing-Out Attachments for Presses, of which the following is a specification.

This invention relates generally to a press 10 which includes a fixed bed and a cross-head or carrier movable in a predetermined path toward and from the bed.

The invention has for its object to provide dieing-out means for a press of this 15 character, including a cutting die attachable to the fixed press bed, and having a continuous cutting edge adapted to cut from leatherboard or other sheet material a blank of any desired outline, and a cutting block 20 of wood or other compressible material, attachable to the cross-head or carrier, and having an acting face adapted to coöperate with the die, the block being rotatively adjustable to present fresh portions of its act- 25 ing face to the die.

The invention is embodied in the improvements which I will now proceed to describe and claim.

Of the accompanying drawings, forming 30 a part of this specification:

Figure 1 shows in perspective the parts or members of an attachment embodying the invention, said parts being shown independently.

35 Fig. 2 is a vertical section, showing the fixed press bed and carrier conventionally and by dotted lines, the members of the attachment being shown in the relative positions they occupy when the carrier is raised.

40 Fig. 3 is a section on line 3—3 of Fig. 2.

Fig. 4 is a top plan view of the die and the bottom plate hereinafter described, showing by dotted lines one of the positions to which the cutting block may be rotatively 45 adjusted.

The same reference characters indicate the same parts in all of the figures.

In Figs. 2 and 3, I have shown conventionally and by dotted lines the fixed bed 12, and 50 the reciprocating cross-head or carrier 13 of a press which may be of any suitable construction, and provided with any suitable means for reciprocating the carrier, the latter moving in a predetermined path toward and from the bed.

The dieing-out attachment preferably in-

cludes all the parts or members shown in perspective by Fig. 1, and described as follows:

14 represents a bottom plate, formed to 60 be seated on the bed 12, and adapted to be secured in any suitable way to said bed, as by screws 15, Fig. 4, engaging tapped orifices (not shown) in the bed, and inserted in holes 16 in the plate.

17 represents a hollow cutting die having a continuous cutting edge, formed as here shown to cut a shoe stiffener blank from sheet material, although it will be understood that the die may be adapted to cut 70 blanks of any desired shape from sheet material. The die is provided with ears 18, detachably secured by screws 19 to the bottom plate, said plate being provided with an aperture 20 coinciding with the opening surrounded by the die, and permitting the escape of the cut blanks. It will of course be understood that the bed 12 is formed to permit the blanks to pass through it.

21 represents a top plate, attachable to the 80 carrier 13, in the example here shown, by means of a shank 22 formed on said plate and entering a socket in the carrier, and set-screws 23 engaging the carrier and shank, as shown by Fig. 3.

To the top plate is detachably secured a 85 stud 24, having a slotted head 25, and a reduced screw-threaded portion 26 engaging a tapped orifice in the top plate.

27 represents a cutting block, of wood or 90 other suitable slightly compressible material, provided with a bearing 29 occupied by the stud 24, the latter constituting a journal on which the block may be turned or rotatively adjusted by hand, to present fresh portions 95 of the lower or acting face of the block to the die 17. The stud head 25 forms an upwardly facing shoulder which confines the upper face of the block 27 against the top plate 21, so that the block is backed by the 100 top plate.

By reference to Fig. 4, it will be seen that the block 27 may be turned to move an indentation 27^a, formed therein by the cutting edge of the die, out of register with the die, and thus present a fresh portion of the acting face of the block to the die. This operation may be repeated until the entire acting face of the block has been utilized.

The upper and lower faces of the block 110 27 are parallel with each other, and each is adapted to serve as the acting face, the block

being invertible and adapted to be secured to the top plate 21 by the described means with either of said faces toward the die.

To prevent the possibility of contact between the stud head 25 and the cutting edge of the die, I provide each of the acting faces of the block with a recess 31 adapted to receive said head, as shown by Figs. 2 and 3, although, as shown by Fig. 4, the relative arrangement of the stud head 25 and die 17 is such that the stud head, if flush with or below the acting face of the block, would be within the opening bounded by the cutting edge when the block contacts with the die. In other words, the head of the stud coincides with the center of the die when the block and die meet.

A washer 32 may be interposed between the stud head 25 and the bottom of the recess 31.

The attachment may include only the members 21, 24 and 27, for use in a press having a cutting die otherwise secured to the fixed bed of the press.

25 I claim:

1. A dieing-out attachment for a press which includes a fixed bed and a reciprocating carrier movable in a predetermined path toward and from said bed, said attachment comprising an apertured bottom plate having means for attachment to said bed, a cutting die separably attached to said plate and coinciding with the aperture thereof, a top plate having an upwardly projecting shank attachable to said carrier, and a cutting block separably attached to and backed by said top plate and pivoted thereto to permit rotative adjustments presenting fresh portions of the acting face of the block to the die.

2. A dieing-out attachment for a press which includes a fixed bed and a reciprocating carrier movable in a predetermined path toward and from said bed, said attachment comprising an apertured bottom plate having means for attachment to said bed, a cutting die separably attached to said plate and coinciding with the aperture thereof, a top plate having an upwardly projecting shank attachable to said carrier, a cutting block backed by said top plate and provided with a central bearing, and a stud occupying said bearing and having a head forming an upwardly facing shoulder confining said block against the top plate, and arranged to be within the opening bounded by the cutting edge of the die when the block and die meet, said stud permitting rotative adjustments of the block and being detachably secured to the top plate to permit the removal of the block.

3. A dieing-out attachment for a press which includes a fixed bed and a reciprocating carrier movable in a predetermined path toward and from said bed, said attach-

ment comprising an apertured bottom plate attachable to said bed, a cutting die separably attached to said plate and coinciding with the aperture thereof, a top plate attachable to said carrier, a cutting block backed by said top plate and provided with a central bearing, and a headed stud occupying said bearing and confining said block against the top plate, said stud permitting rotative adjustments of the block and being detachably secured to the top plate to permit the removal of the block, the block being provided in its acting face with a recess formed to receive the head of said stud.

4. A dieing-out attachment for a press which includes a fixed bed and a reciprocating carrier movable in a predetermined path toward and from said bed, said attachment comprising an apertured bottom plate attachable to said bed, a cutting die separably attached to said plate and coinciding with the aperture thereof, a top plate attachable to said carrier, a cutting block backed by said top plate and provided with a central bearing, and a headed stud occupying said bearing and confining said block against the top plate, said stud permitting rotative adjustments of the block and being detachably secured to the top plate to permit the removal of the block, the block being invertible and provided in each of its opposite acting faces with a recess formed to receive the head of the stud.

5. In an attachment of the character stated, a top plate having means for attachment to a reciprocating carrier, a cutting block backed by said top plate and provided with a central bearing, and a headed stud occupying said bearing and confining said block against the top plate, said stud permitting rotative adjustments of the block and being detachably secured to the top plate to permit the removal of the block.

6. In an attachment of the character stated, a top plate having means for attachment to a reciprocating carrier, a cutting block backed by said top plate and provided with a central bearing, and a headed stud occupying said bearing and confining said block against the top plate, said stud permitting rotative adjustments of the block and being detachably secured to the top plate to permit the removal of the block, the block being invertible to present either of two acting faces to a die located in the path of the carrier.

7. In an attachment of the character stated, a top plate having means for attachment to a reciprocating carrier, a cutting block backed by said top plate and provided with a central bearing, and a headed stud occupying said bearing and confining said block against the top plate, said stud permitting rotative adjustments of the block and being detachably secured to the

top plate to permit removal of the block, the block being provided in its acting face with a recess formed to receive the head of said stud.

5 8. In an attachment of the character stated, a top plate having means for attachment to a reciprocating carrier, a cutting block backed by said top plate and provided with a central bearing, and a headed stud
10 occupying said bearing and confining said

block against the top plate, said stud permitting rotative adjustments of the block and being detachably secured to the top plate to permit removal of the block, the block being invertible and provided in each 15 of its opposite acting faces with a recess formed to receive the head of the stud.

In testimony whereof I have affixed my signature.

HARVEY F. CRAWFORD.
